UNITED STATES PATENT OFFICE.

CHARLES L. HOOPER, OF ROCHESTER, NEW YORK, ASSIGNOR TO VACUUM OIL COMPANY, OF NEW YORK, N. Y., A CORPORATION OF NEW YORK.

FILLING MACHINE.

Application filed December 18, 1920. Serial No. 431,749.

To all whom it may concern:

Be it known that I, CHARLES L. HOOPER, a citizen of the United States, and resident of Rochester, in the county of Monroe and State of New York, have invented certain new and useful Improvements in Filling Machines, of which the following is a specification.

The present invention relates to filling machines of the type in which one or more receptacles are arranged upon a suitable support and a number of filling devices or nozzles corresponding to the number of receptacles are associated with the support for discharging the material into the receptacles, provision being made by which the relative movement between the receptacle support and nozzle takes place in order to cause the nozzle to enter the filling openings of the receptacles. An object of this invention is to provide in connection with a machine of the class described, a drip collector or pan which will move automatically between the nozzles or filling devices and the receptacle support as these two parts are moved away from each other and will be displaced automatically from between said parts as the latter are moved toward each other, whereby drippings from the filling devices will not fall upon the receptacles on the support.

To this and other ends the invention consists of certain parts and combinations of parts, all of which will be hereinafter described, the novel features being pointed out in the appended claims.

In the drawings:

Fig. 1 is an end view of a machine constructed in accordance with this invention; Fig. 2 is a vertical section on the line 2—2, Fig. 1, parts below such section being shown in side elevation;

Fig. 3 is an enlarged fragmentary section on the line 3—3, Fig. 1;

Fig. 4 is a detail view illustrating the operating mechanism for the drip pan; and

Fig. 5 is a section on the line 5—5, Fig. 3.

Referring more particularly to the embodiment herein illustrated, 1 indicates the base frame of the machine which has a table 4 or other support for the cans arranged thereon, this support being formed in any suitable manner and preferably embodying a plurality of parallel spaced bars 5 connected by cross pieces 5. Below this

table is arranged a pan 6 into which any drippings may fall. The receptacles 7, in this instance in the form of cans, are arranged in a tray 8 which is moved by hand along the support or table 4, the tray carrying preferably a number of receptacles.

The filling means, in this instance, comprises a number of nozzles 9 corresponding preferably to the number of the cans 7 in the tray 8 and connected with a supply tube 10, each nozzle having a vent tube 11 connected therewith and leading to a vent pipe 12 which extends into the pan 6. This construction is old and well-known and does not of itself form part of the present invention. In order that the supply tube 10 may move toward and from the support 4, the latter has end pieces 13 each carrying a guide member 14 operating on vertical guides 15 formed on side frames 1^a which project upwardly from the base 1.

For effecting a relative movement between the support 4 and the filling devices 9, a lever 16 is mounted at one side of the machine and is secured to a shaft 17. This lever carries a locking pawl 18 operable through a hand piece 19 and adapted to cooperate with a fixed rack 20 on the frame of the machine. The shaft 17 extends transversely of the machine below the table 4 and has, in this instance, two arms 21 which are pivoted at 22 to links 23, the latter being pivoted on headed pins 24 secured to the guide pieces 14. The turning of the shaft 17 in one direction lowers the nozzles 9 into the filling opening 7^a of the cans or receptacles 7, while the turning of the shaft 17 in the opposite direction, elevates said nozzles.

The nozzles which are formed in a well-known manner and will not be described in detail, automatically close as they pass from the filling openings of the cans or receptacles and automatically open as they are introduced into said filling opening. There is, however, a certain amount of dripping from the nozzles as the latter move upwardly and this ordinarily falls upon the cans or receptacles, necessitating the wiping of such cans to remove the dripping.

According to this invention, a drip pan is automatically interposed between the nozzles and the support for the receptacles upon the relative movement between the nozzles and the support away from each other, and

this drip pan is also automatically removed from between the nozzles and the support for the receptacles as the relative movement between the nozzles and the support 5 takes place to introduce the nozzles into the filling openings of the receptacles.

The drip pan, in this instance, comprises a sheet metal plate 25 curved as shown in the drawings and secured to two rods 26, the 10 sheet metal being extended at 27 to one side of one of the rods. The pan is guided for movement transversely of the line of movement of the nozzles and to this end, brackets 28 are secured in pairs to the side frames 15 1^a and project inwardly, each pair having its inner ends connected by guides 29 which are spaced from the side frames 16 in order that the guide pieces 14 may have space for movement. The guides 29 receive the 20 ends of the bars or rods 26 and at opposite ends of each guide, stops 30 are provided to confine the pan to the guides.

The automatic movement of the pan may be effected in any suitable manner. In this 25 instance, at one side of the pan a link 31 is pivoted on one of the rods 26 and to this link is pivoted at 32, an operating member 33. This operating member is in turn pivoted at 34 to one of the side frames 1^a. A 30 connection is provided between this operating member 33 and the operating mechanism which effects relative movement between the filling nozzles 9 and the receptacle support 4. This connection, in this instance, embodies an arm 35 extending from the member 33 and a recess or cam opening 36 arranged at the upper end of the arm 35 at a slight angle to one side of the arm. This cam opening or notch 36 is adapted to 35 receive the headed projection 24, forming the pivotal connection between the link 23 and the guide member 14, when said pivotal connection moves upwardly, causing the member 33 to swing on its pivot 34 and through the link 31 to shift the drip pan 25 between the nozzles 9 and the support 4. On the lowering movement of the nozzles, the projection 24 engages the walls of the cam slot 36 and shifts the member 33 to dis- 40 place the drip pan 25 from beneath the nozzles 9. The movement of the drip pan in both instances is quick and occurs during the first part of the descent of the nozzles to shift the pan away from the path of the nozzles and during the latter part of the ascent of the nozzles so that the nozzles will have passed out of the path of the drip pan before the latter moves beneath them.

From the foregoing it will be seen that 60 there has been provided a filling machine in which a drip pan is employed which au-

tomatically shifts between the nozzles or filling devices and the support for the cans or receptacles as a relative movement between the nozzles and the support, one away 65 from the other, takes place, this drip pan also moving automatically from between the nozzles or filling devices and the support for the can or receptacles as the relative movement between such filling devices and support takes place, one toward the other, so as not to interfere with such relative movement. While in the present embodiment the relative movement between the filling devices and the receptacle support is effected by 70 moving the nozzles toward and from the support, it will be apparent that the present invention is not limited to this relative movement and it is desired to be understood that any relative movement between 75 these two parts is within the scope of this invention.

What I claim as my invention and desire to secure by Letters Patent is:

1. A filling machine comprising a receptacle supporting table, a plurality of filling nozzles arranged above and guided toward and from the table, a drip collector guided at opposite ends into and out of the path of movement of the nozzles, a pivotally mounted operating member for the drip collector having a cam groove, and mechanism for moving the nozzles toward and from the table having a projection adapted to operate in said cam groove for moving the drip collector out of the path of the nozzles as the latter move toward the table and for moving the drip collector toward the nozzles as the latter move away from the table.

2. A filling machine comprising a receptacle supporting table, uprights projecting upwardly on opposite sides of said table, a plurality of filling nozzles, guide members carried by the nozzles and guided on the uprights, a shaft mounted to turn beneath the table, arms carried by said shaft, links connecting said arms and the guide members, guides arranged on the inner faces of the uprights, a drip collector guided at opposite ends on said guides, and an operating member pivoted to one of the uprights and having a link connection with the drip collector, said operating member having a cam groove receiving the headed pivot of one of the links on a guide member to effect the movement of the drip collector between the nozzles and the receptacle supporting table and to effect the movement of the drip collector out of the path of the nozzles as the latter move toward the receptacle supporting table.

CHARLES L. HOOPER.
